CLAIM

The ornamental design for fascia gun as shown and described.

DESCRIPTION

The product indication is a fascia gun.

Figure 1.1 is a perspective view of a fascia gun, showing my new design.

Figure 1.2 is a front view thereof.

Figure 1.3 is a back view thereof.

Figure 1.4 is a left view thereof.

Figure 1.5 is a right view thereof.

Figure 1.6 is a top view thereof.

Figure 1.7 is a bottom view thereof.

(Continued)

The broken lines shown in the drawings illustrate portions of the fascia gun that form no part of the claimed design.
